INVENTOR

George A. Seib
By Jacob Felber
HIS ATTORNEY

UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING-MACHINE.

1,391,798.

Specification of Letters Patent. Patented Sept. 27, 1921.

Application filed May 1, 1920. Serial No. 378,174.

To all whom it may concern:

Be it known that I, GEORGE A. SEIB, citizen of the United States, and resident of Ilion, in the county of Herkimer and State 5 of New York, have invented certain new and useful Improvements in Typewriting-Machines, of which the following is a specification.

My present invention relates to carriage 10 governors for typewriting machines, and its main object is to provide new and improved carriage governing or controlling mechanism for regulating the speed of the traveling element or carriage of typewriting 15 or similar machines.

To the above and other ends which will hereinafter appear, my invention consists in the features of construction, combinations 20 of devices and arrangements of parts to be hereinafter described and particularly pointed out in the claims.

In the accompanying drawings which illustrate the preferred form of my invention applied to a machine generally resembling 25 the Remington typewriter,

Figure 1 is a fragmentary front to rear vertical sectional view showing parts of a typewriting machine embodying my invention.

Fig. 2 is a fragmentary plan view illustrating my invention and associate parts.

Fig. 3 is a vertical longitudinal section through the governor, said view being taken on a plane indicated by the dotted line 35 3—3 in Fig. 2 and looking in the direction of the arrow at said line.

Fig. 4 is a perspective view illustrating the parts of the governor separated from one another.

Fig. 5 is a plan view corresponding to Fig. 2 and showing the cover swung away to expose the interior of the cup or housing.

Fig. 6 is a fragmentary plan view corresponding to Fig. 5 but showing the relationship of parts of the governor when the carriage is moving backward or in reverse direction.

Figs. 7 and 8 are perspective views of details.

Figs. 3 and 4 are drawn on a larger scale than the other views.

The main frame of the machine, as illustrated in Fig. 1, comprises a base 1, posts 2, and a top plate 3 above which are fixed

grooved trackways 4 that coöperate through 55 anti-friction rollers 5 with a traveling element or platen carriage comprising a rectangular frame consisting of front and rear grooved bars and connecting side bars, the rear bar 6 and one of the side bars 7 alone 60 being illustrated. Suitable printing instrumentalities (not shown) coöperate with the front face of the platen and are adapted to actuate the escapement mechanism which during letter feeding controls the leftward step-by-step movements of the carriage under the influence of suitable carriage motor or impelling mechanism comprising a spring drum 8 pivoted on a stationary bracket 9 and connected by a band or strap 70 8a with the carriage. A releasable feed rack 10 is secured to arms 11 fulcrumed at 12 in ears 13 fixed to the rear part of the carriage. Said feed rack normally meshes with the top or upper side of a toothed pinion 75 14 (Figs. 2 and 3) that is secured to an escapement wheel shaft (not shown), said shaft bearing in a bracket 15 fixed to the top plate, the rear end of said shaft being operatively connected with an escapement 80 wheel 16, comprised in the escapement mechanism referred to above.

Tabulating mechanism bearing a general resemblance to the tabulating mechanism disclosed in my prior Patent No. 1,132,286, 85 dated Mch. 16, 1915, and embodied in some Remington typewriting machines, is illustrated in Fig. 1, said tabulating mechanism comprising a rectangular stop bar 17 mounted on arms or brackets 18 secured 90 to the carriage and extending rearward therefrom. The stop bar is notched or toothed and is adapted to receive a plurality of tabulating or column stops which may be adjusted at suitable intervals along said stop bar, only one of said column stops 19 being shown, said column stop being provided with a rearwardly projecting stop proper 20. Coöperative with the column stops are a set of frame stops or stop members arranged 100 one above the other, only the lowermost frame stop, 21 being shown, said frame stops being suitably mounted in the head portion 22 of a stop frame 23 which is detachably secured to the main frame of 105 the machine at its rear. The frame stop 21 and its associates are each adapted to be actuated by a separate train of key actuated

devices, said train comprising an upright lever member 24 pivoted between its ends at 25 on the frame 23. Each lever 24 has associated with it a restoring spring 26 and 5 the upper end of said lever co-operates with its frame stop to project it forward into the path of one of the column stops when the associate tabulator key is operated. The lower end portion of the lever 24 projects for- 10 ward horizontally at right angles to the body of the lever, said lower portion being pivotally connected at 27 at the rear end of a horizontally disposed link 28. The forward end of said link is pivotally connected 15 at 29 with an angular lever member 30 ful- crumed at 31 and terminating at its front end in a forwardly extending finger 32. This finger slidably engages in an opening in a vertically disposed key stem 33 pro- 20 vided at its upper end with a cap or tabu- lating key 34, the upper end portion of said key stem passing through an opening in a guide plate 35 and the lower end being guided by a stationary guide plate 36 25 through which it passes. It will be under- stood that there are five tabulator keys 34 and associate trains of devices, each tabu- lator key and its train controlling one of the frame stops to project it into the path 30 of one of the carriage or column stops of which there are five also.

It is preferred in the present instance to release the carriage automatically from the control of the escapement whenever one of 35 the tabulator keys 34 is actuated, this train of releasing mechanism including the gov- ernor or speed regulator itself. The releasing mechanism comprises a U-shaped bail composed of a horizontal bar or body por- 40 tion 37 and two vertically disposed arms 38 pivoted at 31, the arrangement being such that the bail depends from its pivot and the horizontal releasing bar 37 is disposed be- hind the vertical portions of the levers 30 45 and in position to be actuated by each of them. A coiled spring 39, connected to the bar 37 and anchored at its forward end to the plate 36, tends constantly to swing the releasing bail forward and maintains the 50 front edge of the bar 37 in contact with the levers 30. An ear 40, depending from the bar 37, has pivotally connected to it at 41 the front end of a rearwardly extending link 42, the rear end of said link being pivotally connected at 43 with an angular lever 44 pivoted at 45 to a bracket 46 that is se- 55 cured to the rear portion of the base 1. The lever member 44 has a forwardly extending arm or finger 44¹ to which is pivotally con- 60 nected at 47 the lower end of an upwardly extending link 48, the upper portion of said link being curved or offset rearwardly and projecting through an opening 49 in the top plate 3. The upper end of said link 48 is 65 formed with a lateral hole which receives

a pin 50 projecting laterally from the rear- 70 wardly extending portion or ear 51 of an angular bracket 52 that is secured by screws 53 to the right-hand side of the governor body. A spring clip or finger 54, riveted or otherwise secured to the side of the link 48, maintains said link engaged with the pin 50 and prevents accidental disconnection.

Referring more especially to Figs. 1 to 4, it will be seen that the governor or car- 75 riage speed regulator comprises a body, designated generally as 55, preferably of cast metal, the body comprising a head portion 56 and a forwardly extending barrel or stem 57 near the forward end of 80 which is a cylindrical cross bar or bearing arm 58, integral with the barrel at its under side and projecting laterally at right angles from it. The ends of the cross bar 58 are formed with depressions or seats which re- 85 ceive the reduced inner bearing ends 59 of screws 60, said screws having also threaded portions 61 of larger diameter which are screwed into the upstanding ears 62 of a U-shaped bracket 63, said bracket being 90 formed with an open ended slot 64 and a closed slot 65, which slots respectively re- 95 ceive headed screws 66 and 67 that are threaded into the top plate 3 and adjustably fix the bracket 63 thereto. The construc- 100 tion is such that the screws 60 when threaded into the bracket ears 62 are fixed thereto and the screw ends 59 which are smooth and without threads provide in effect stationary pintles on which the governor contrivance 105 as a whole may bear and may be swung up and down, its normal position being at an incline to the horizontal, as illustrated by full lines in Fig. 1, this position being main- 110 tained by the spring means 39 acting through the connected train of devices. The barrel 57 is bored out, as indicated at 68, to receive a shaft 69 of considerably less diameter than the bore 68. The forward end portion of 115 the shaft 69, as best appears in Fig. 7, is reduced in diameter, the reduced portion 70 and the body portion of the shaft forming a shoulder. At diametrically opposite sides of the reduced end portion 70 the body 120 of the shaft is cut away or flattened, as in- 125 dicated at 71, the distance between the flats substantially corresponding to the diameter of the portion 70. Said portion 70 receives a pinion member 72, shown de- 130 tached in Fig. 8, and comprising a small gear or pinion proper 73 and a sleeve or bearing portion 74. The pinion member is bored out as indicated at 75 to fit over the shaft end 70 and the end of the sleeve 74 is slotted, as indicated at 76, to co-operate 135 with the flattened portion 71 of the shaft so as to prevent the pinion member from turning relatively to the shaft. After the pinion member has been put in place the end of the shaft part 70 is upset to fill out 140

the outer end of the bore 75 which is flared slightly, the construction being such that as a result of this upsetting the pinion member and shaft become substantially integral. The 5 sleeve portion 74 fits in and is adapted to turn freely in the bore 68, said sleeve being in effect the forward bearing end of the shaft. An oil hole, indicated at 77 (Fig. 3) may be provided for oiling the bearing. The 10 rear portion of the body 55 is cut out at its under side, as indicated at 78, this cut-out exposing part of the shaft 69. Mounted on the exposed part of the shaft within the cut-out 78 is a collar 79 which is secured in 15 place by a set screw 80, the inner end whereof abuts against a flattened face 69^a of the shaft. The forward face of the collar 79 contacts with the front wall or side of the cut-out 78 and prevents forward endwise 20 movement of the shaft 69, rearward endwise movement being prevented by coöperation of the back of the pinion 73 with the end of the barrel 57. Also arranged within the cut-out 78 and mounted on the shaft 69 is 25 a gear member 81, this gear member being disposed back of the collar 79 and comprising a circular set of crown teeth 82 and a collar portion 82^a which receives a set screw 83 that abuts against the flat 69^a and fixes 30 the gear member 81 to the shaft 69. It will be observed from Fig. 3 that the rear end portion of the shaft 69 bears in a bearing opening 84 formed in the casting or body 55 back of the cut-out 78. The top of the 35 head portion 56 of the casting or body 55 is cut out to provide a shallow circular depression or seat, indicated at 85, and centrally of this shallow seat is a deeper depression or seat of lesser diameter, indicated at 86, 40 this depression 86 connecting with the cut-out 78 as will be understood clearly from Figs. 3 and 4. Arranged centrally in this depression 86 is an upright bearing post, stud or screw 87, the lower end of which is 45 reduced and threaded so that it may screw into a tapped hole 88 in the casting, thereby securing the post in fixed position. This post or stud 87 provides a bearing for a pinion 89, which is formed with a hole to 50 fit over and bear on the post, and is seated in the depression 86, said pinion meshing with the crown gear 82. As best appears in Fig. 4, the upper end of the pinion 89 is reduced and squared to provide a rectangular head 90 that accommodates a spider, fan or rotary pushing device 91. This spider which is accommodated in the shallow seat 55 comprises arms 92 arranged at right angles to each other, there being four of these 55 arms. Centrally the spider is formed with a square hole indicated at 93 to fit over the squared head 90 and engage with the sides thereof, the spider being adapted to rest on the upper surface of the pinion teeth 89 and 60 being forced to turn when the gear 89 turns by reason of its engagement with the head 90. The length of the arms 92 of the driver is such that they do not contact with the inner circular wall or boundary of the casing or housing within which they are seated. 70 Disposed within the spaces formed by the arms 92 are slideable detached pieces or members 94, there being four of these members. These members which are loose in the casing resting on the bottom of the depression 85, 75 are generally triangular in shape, having two straight faces at right angles to each other, which straight faces are adapted to contact with the faces of the arms 92. The third or outer face of the plate or member 80 94 is curved, preferably conforming to an arc of a circle somewhat less in diameter than the circular curve of the wall of the seat 85 with which said curved face is adapted peripherally to engage. The dimensions 85 of the members 94 are such that when they are nearest the center of rotation, which center of course is coincidental with the axis of the post 87, each of said members 94 may contact at both of its straight faces with the 90 arms 92 and then the curved surfaces of said members are separated from or out of contact with the circular wall of the seat 85. The housing, casing, or cup within which are arranged the detached members 94 and 95 the spider 91 is provided with a circular cover 95, which is pivoted at one side on a shouldered screw 96 that is received in an enlargement 97 of the rim of the housing while at the diametrically opposite side a 100 shouldered screw 98, received in a tapped hole in a corresponding enlargement 97, is adapted to coöperate with a hook 95^a on the cover so as to maintain the cover closed, this being insured by screwing down the screw 105 98 until it engages frictionally with the surface of the cover surrounding the hook. In order to enable the cover to be swung back to the Fig. 5 position and expose the interior of the housing, it is only necessary 110 slightly to loosen the screw 98, after which the cover may be pulled away, turning on the screw 96 as a center.

Referring to the operation of the mechanism, it will be understood that normally 115 during back and forth movements of the carriage the feed rack 10 is pressed down and maintained in normal engagement with the feed pinion 14 while the pinion 73 of the governor lies below and out of engagement with the said rack 10. Supposing one of the tabulator keys 34 to be actuated or pushed down until the lever 30 is arrested by contact with the stop or pad 99, this actuation will result, as has been explained, in 120 projecting the connected frame stop, such as 21, into the path of the associate stop as 20 on the traveling carriage, and will likewise automatically effect the release of the carriage and the precedent connection thereto 130

of the governor or speed regulator through the described train of connections comprising the bail 37, 38, the link 42, the lever 44, and the link or connector 48. Said connector 48 will be drawn down from the full line to the dotted line position in Fig. 1 and will swing the governor on its pivot 60 from the inclined full line position of Fig. 1 to the substantially horizontal position illustrated by 10 dotted lines in said Fig. 1 and by full lines in Fig. 3. This swinging movement of the governor will bring the pinion 73 into engagement with the teeth of the rack 10 and will swing the rack upward, disengaging it 15 from the feed pinion 14 while connecting it through the pinion 73, shaft 69, gear 81 and pinion 89 with the pushing device or spider 91. As a result, if the carriage be permitted 20 to run freely under the influence of its spring drum 8 toward the left, the pushing device 91 will turn in the direction indicated by the arrow in Fig. 5, this turning movement rendering one of the contact faces of each arm 92 effective. The effective contact faces aforesaid are radially disposed; 25 that is to say, they are coincident with radial lines passing through the center of rotation of the device 91, such lines being indicated in Fig. 5 by the dotted lines *a a*. These 30 radial contact faces *b* will act against the proximate straight faces of the slideable or detached friction pieces or plates 94 and will tend to push these pieces around ahead 35 of said arms, the force applied through the arms to the pieces following substantially a path concentric with the center of rotation of the device 91. As the pieces 94 are pushed ahead they will be free to be acted upon by 40 centrifugal force and by this force alone said pieces will be forced outward until their curved peripheral faces or edges frictionally engage with the inner curved wall or face of the casing or depression 85. The amount of pressure exerted will of course depend on 45 the speed at which the device 91 is turned, this speed corresponding with or being relative to the speed of advance movement of the carriage during its tabulating run. As the speed increases the pressure will increase 50 and as the speed diminishes the pressure will lessen, so that it will be seen that a self-regulating speed device or governor for controlling the speed movement of the carriage is provided, the result being that the carriage 55 will move smoothly and uninterruptedly and will be arrested by its coöperating tabulator stops without shock or jar. On releasing the tabulator key the parts will be restored to normal position, as has been described, the limit of movement being determined by the contact of a finger 30^a on the lever 30 with a stationary pad or stop 100.

The present invention also affords means for governing or controlling the speed of 60 the carriage during reverse tabulating. Sup-

posing that one of the tabulating keys be actuated, as has been described, to project a frame stop and connect the governor with the carriage, and that then the operator pushes or thrusts the carriage by hand in reverse direction or from left to right. Then the rotary device 92 will turn in reverse direction, as indicated by the arrow in Fig. 6, and the other contact faces *c* of the arms 92, 70 opposite the radial contact faces *b*, will become effective on the loose or detached friction pieces or plates 94. These opposite contact faces *c*, which are at this time effective, 75 have a different pressure angle from the faces *b*. The faces *c* are not radially arranged but are offset or disposed at angles to radii passing through any point on their surfaces and through the center of rotation. Owing to the fact that the faces *c* are non- 80 radial they have a different action on the sliding plates than the radial faces *b*, and this different action causes greater pressure of the peripheral faces or edges of the plates against the interior of the casing or cup than is caused by the radial faces *b*. The result 85 is that when the carriage is returned and the speed governor is connected thereto, the operator will encounter considerable resistance to the return of the carriage and thus be prevented from throwing it too violently to the right against the reverse tabulator stops. 90

It will be perceived that by the present invention there is provided an exceedingly effective speed regulator or speed controller 100 for the traveling carriage, which governor is effective both during tabulating runs of the carriage in one direction under the impulse of its spring drum and is also effective during return movements of the carriage in the opposite direction. The governor is 105 comparatively simple and inexpensive, is strongly constructed and consists of few parts which are not liable to become disarranged or get out of order, and the motions are transmitted through a comparatively short train of mechanism which reduces friction and unnecessary work and conduces to promptness and accuracy of 110 operation. 115

Various changes may be made without departing from my invention.

What I claim as new, and desire to secure by Letters Patent, is:

1. A governor for regulating the speed of a traveling carriage; said governor comprising a loosely mounted movable friction surface, a relatively stationary friction surface, and operating means for insuring frictional engagement of said surfaces through centrifugal force alone. 120

2. A governor for regulating the speed of a traveling carriage comprising a casing, a piece slideable within said casing, a pushing device and means for moving said device to 130

- push said piece ahead of it and cause it through centrifugal force alone to frictionally engage the inner wall of said casing.
3. In a carriage speed governor, the combination of a housing, a series of detached pieces arranged within said housing and having surfaces adapted to engage with the wall of said housing, and a rotary driver adapted to carry said pieces around the housing and by centrifugal force alone cause their surfaces to engage frictionally with the wall of said housing.
4. A governor for regulating the speed of a traveling carriage comprising a casing, a part loose in said casing and capable of centrifugal action, and means for employing the centrifugal force of said loose part to press against the face of said casing and to force said part to move relatively to said casing when thus frictionally pressed against it, the retarding effect on the carriage being due solely to the centrifugal force of said loose part.
5. A governor for regulating the speed of a traveling carriage comprising a circular casing, a slideable device within said casing provided with a straight face and a curved face, and a rotary arm provided with a radial face coöperative with said straight face to insure frictional engagement of said curved face with the circular inner wall of said casing.
6. A governor for regulating the speed of a traveling carriage comprising a casing, a plurality of angularly disposed rotary arms within said casing, and pieces loosely confined between said arms, the rotary movements of said arms pushing against said pieces and compelling them through the action of centrifugal force alone to frictionally engage with the inner wall of said casing.
7. A governor for regulating the speed of the traveling carriage comprising a casing, a plurality of pieces loose within said casing, a pushing device provided with a plurality of arms one for each of said pieces, means for moving said arms to render them effective, said means comprising a pinion with which said device is connected through one part having a portion engaging in an opening in the other part, and a pivoted cover for said casing, which cover may be swung aside to permit the removal of said pieces, said device and said pinion.
8. A governor for regulating the speed of a traveling carriage comprising a casing, a single member composed of a plurality of arms angularly related to each other, said device being pivotally mounted within the casing, pieces supported on the floor of the casing and loosely confined between said arms, and automatically operative connections between said device and the traveling carriage, said pieces being forced into frictional coöperation with the inner periphery of said casing through the action of centrifugal force alone.
9. A governor for regulating the speed of the traveling carriage comprising a rotary arm having two contact faces, one contact face being radial and the other offset from a radial position, two pieces separate from said arm and against which said contact faces are adapted to push, and a relatively stationary surface with which said pieces are adapted to frictionally coöperate when acted upon by said arm.
10. A governor for regulating the speed of a traveling carriage comprising a casing, a plurality of angularly related rotary arms within said casing, each arm having two contact faces, one radial and one offset from a radial position, and pieces loosely confined between said arms, the rotary movements of said arms pushing against said pieces and compelling them through the action of centrifugal force to frictionally engage with the inner wall of said casing.
11. A governor for regulating the speed of a traveling carriage comprising a casing, a plurality of angularly related rotary arms within said casing, each arm having two contact faces, one radial and one offset from a radial position, and pieces loosely confined between said arms, the rotary movements of said arms pushing against said pieces and compelling them through the action of centrifugal force to frictionally engage with the inner wall of said casing, said pieces being provided each with two straight faces for respective contactive engagement with the radial contact face on one of said arms and the offset contact face on one of said arms.
12. A governor for regulating the speed of a traveling carriage comprising a casing, a plurality of angularly related rotary arms within said casing each arm having two contact faces, one radial and one offset from a radial position, pieces loosely confined between said arms, the rotary movements of said arms pushing against said pieces and compelling them through the action of centrifugal force to frictionally engage with the inner wall of said casing, and means for rotating said arms oppositely to render their radial contact faces effective in alternation with their offset contact faces on said pieces.
13. In combination with a traveling carriage, a pivoted speed governor formed with a depression, a contact arm in said depression, a detached slideable friction piece adapted to be controlled by said arm, and key actuated means for swinging said governor on its pivot and connecting said carriage with said arm.
14. In a typewriting machine, the combination of a traveling carriage, a pivoted key controlled governor provided with a cup or

depression, a rotary arm arranged in said depression, a friction piece controlled by said arm, and means for connecting said arm with said carriage when a governor is swung on its pivot, said connecting means comprising a pinion rigid with said arm, a shaft mounted on said governor and provided with a pair of gears, one of said pair of gears co-operating with said pinion and the other of 10 said pair of gears being adapted for connection with the carriage.

15. The combination of a carriage, a releasable feed rack mounted thereon, tabulating mechanism comprising a key controlled stop, a pivotally mounted speed governor controlled automatically by said tabulator mechanism and comprising a casting formed with a seat or depression, governing devices within said depression one of said 20 governing devices carrying a pinion, and means adapted to connect said pinion with said rack, said connecting means comprising a shaft mounted on said casting, a crown gear at one end of said shaft constantly 25 meshing with said pinion, and a gear at the opposite end of said shaft engageable with said rack, the construction being such that when the tabulating mechanism is actuated said last recited gear engages with said rack to disconnect it from the escapement mechanism of the machine and to connect it with said governing devices.

16. The combination of a carriage, a re-

leasable feed rack mounted thereon, tabulating mechanism comprising a key controlled stop, a pivotally mounted speed governor controlled automatically by said tabulator mechanism and comprising a casting formed with a seat or depression, governing devices within said depression one of said 30 governing devices carrying a pinion, and means adapted to connect said pinion with said rack, said connecting means comprising a shaft mounted on said casting, a crown gear at one end of said shaft constantly 35 meshing with said pinion, and a gear at the opposite end of said shaft engageable with said rack, the construction being such that when the tabulating mechanism is actuated said last recited gear engages with said rack to disconnect it from the escapement mechanism of the machine and to connect it with said governing devices.

Signed at Ilion, in the county of Herkimer, and State of New York this 26th day 40 of April, A. D. 1920.

GEORGE A. SEIB.
